DENTAL PASTE MIXING TOOL

Odaville Yates, Portland, Oreg.

Application November 14, 1955, Serial No. 546,597

1 Claim. (Cl. 32—40)

This invention relates to mixing tools generally and pertains more particularly to a tool adapted as a dental accessory for mixing dental paste, such as the paste used in the filling of teeth, for making denture casts and the like.

One object of this invention is to provide a mixing tool of the character described which can be readily applied to a dental hand drill such as is ordinarily used by dentists.

Another object of this invention is to provide an improved mixing tool including a substantially flat circular body portion or paddle having an elongate stem rigid therewith and projecting radially therefrom for connection with an associated hand drill, the paddle including diametrically opposed sectors curved outwardly of and in opposite directions from the main body portion thereof for adapting the mixing paddle for high speed operation.

A further object of this invention is to provide an improved mixing device constructed in accordance with the preceding paragraph wherein the body is also provided with a relatively large central opening which permits some of the paste being mixed to pass therethrough so that when the mixer is driven at a high rate of speed, it will not create a void in the paste or material being mixed but will substantially continuously permit some of the material to be presented for mixing by the paddle or body.

A still further object of the invention is to provide a mixing tool for use with dental engines and having simplicity of design, economy of construction and efficiency in operation.

The novel features that are considered characteristic of the invention are set forth with particularity in the appended claim. The invention itself, however, both as to its organization and its method of operation, together with additional objects and advantages thereof, will best be understood from the following description of a specific embodiment when read in connection with the accompanying drawing, wherein like reference characters indicate like parts through the several figures and in which:

Figure 1 is an elevational view with parts broken away showing the improved mixing tool connected with a conventional dentist's hand drill and showing the same in operation;

Figure 2 is a sectional view taken substantially along the plane of section line 2—2 of Fig. 1;

Figure 3 is a perspective view of the improved mixing tool, and

Figure 4 is an end view taken substantially along the plane of section line 4—4 of Fig. 3.

Referring now more particularly to the drawing, specifically to Figs. 3 and 4, the improved mixing tool will be seen to consist essentially of a circular and generally flat disc-like body or paddle 1, having formed integrally therewith or rigidly attached thereto a stem member 2, the stem

2

projecting radially from the body and in a common plane therewith. The stem 2 is connected to the body 1 at a peripheral point 3 thereon as is clearly shown in Fig. 3.

The body 1 is provided with a pair of diametrically opposed tip portions 4 and 5 which are curved at 6 outwardly in opposite directions from the remaining major portion of the body 1 located therebetween. These tip portions are in the shape of sectors of the circular body 1 and constitute only a minor portion of the entire body.

10 Thus, the body is substantially S-shaped in cross section as will be most clearly evident from Figs. 2 and 4.

In addition to the two above-mentioned tip portions 4 and 5, the body may be, and preferably is, provided with a relatively large central opening 8 which is concentric therewith and which materially aids in adapting the paddle or mixing device for high speed operation.

When in use, the above-described device is intended for utilization in conjunction with a conventional dentist's hand drill 10 having the usual chuck 9 thereon. The free end of the stem 2 is securely held within the chuck 9 so that the paddle 1 may be rotated at high speeds.

Reference numeral 12 designates generally a conventional mixing bowl which, in Fig. 1, is shown to contain a quantity of paste-like material 7 to be mixed. The paddle 1 is immersed in the material 7 and the high speed rotation of the same will thoroughly mix the material 7. As will be clear from Fig. 1, the concentric opening 8 in the body 1 will permit the material in the region thereof to pass through the body 1 as the same is rotated and will thus 30 cause some of the paste material to pass continuously through the paddle for subsequent mixing action thereon by the body. This action substantially eliminates the possibility of the paddle forming a void in the paste material 7, which would otherwise tend to occur due to 35 the high speed of rotation of the paddle.

Thus, for all practical purposes, the paddle 1 may be maintained in a stationary position within the mixing bowl 12, whereas at the same time the mixing action thereof will be substantially continuous. Of course, during 40 actual operation, the paddle will be moved about in the bowl to more rapidly effect the thorough mixing of the entire contents thereof. It has been found that by utilizing the above mentioned tool, mixing of paste-like material is effected much more efficiently and rapidly than 45 by the conventional practice of mixing the paste by a hand manipulated spoon, pestle or the like.

Although a certain specific embodiment of the invention has been shown and described, it is obvious that many modifications thereof are possible. The invention, therefore, is not to be restricted except insofar as is necessitated by the prior art and by the spirit of the appended claim.

What I claim is:

A mixing tool comprising a substantially flat, circular paddle, an elongate cylindrical stem rigid with and extending radially from the periphery of said paddle, said paddle having a pair of diametrically opposed, oppositely directed tip portions curved outwardly of the remaining major portion of the paddle, and said paddle having a concentric central opening to permit material being mixed 55 to pass therethrough for substantially continuous presentation to the paddle.
